UNITED STATES PATENT OFFICE.

JONATHAN J. SMITH, OF DES MOINES, IOWA, ASSIGNOR OF ONE-HALF TO OSCAR F. PETERSEN, OF DES MOINES, IOWA.

HOT-BLAST DOWNDRAFT-FURNACE.

1,351,803.

Specification of Letters Patent. Patented Sept. 7, 1920.

Application filed March 5, 1919. Serial No. 280,693.

To all whom it may concern:

Be it known that I, JONATHAN J. SMITH, citizen of the United States of America, and resident of Des Moines, Polk county, 5 Iowa, have invented a new and useful Improvement in Hot-Blast Downdraft-Furnaces, of which the following is a specification.

The object of this invention is to provide 10 improved means for increasing the efficiency of furnaces burning bituminous coal or other fuel high in volatile carbon.

My invention has for its further object 15 the ventilation of a room or compartment adjacent to a furnace, whereby the foul air may be withdrawn from said room and passed through the combustion chamber of said furnace.

My invention consists in the construction, 20 arrangement and combination of elements hereinafter set forth, pointed out in my claims and illustrated by the accompanying drawing, in which—

Figure 1 is an elevation, partly in section, illustrating the application of my improvement to a furnace and adjacent room. Fig. 2 is a horizontal section on the indicated line 2—2 of Fig. 1. Fig. 3 is a vertical section on the indicated line 3—3 of Fig. 1.

30 The improvement hereinafter described may be employed, singly or in multiple, in connection with any selected form of furnace, particularly such as may be used in heating a building by hot-air circulation, 35 steam or hot water radiation, and in this connection the furnace shown is typical of one form only.

In the construction of the devices as shown the numeral 10 designates generally 40 a furnace or heater of the hot-air type and it may be of any desired and suitable construction, preferably modified in the particulars herein pointed out. The furnace 10 preferably is lined throughout its entire interior height by an overlay 11 of heat-resisting plastic material such as fire-clay and a smoke-discharge 12 is provided in said lining and communicates with a drum 13 having a smoke-discharge 14 near the lower 45 end thereof adapted to communicate with a flue or chimney, not shown, for draft purposes. Any suitable casing or jacket may be used, a portion 15 thereof being shown. The furnace 10 preferably is provided with 50 a dome 16 formed with a central opening

and a pipe 17 is mounted vertically in said opening and projects above and below said dome. A flanged collar 18 is fixed to the upper surface of the dome 16 and surrounds said pipe 17 and the pipe is secured to said 60 collar by a set screw 19. A conductor or conduit pipe 20 communicates at one end with the upper end of the pipe 17 and at its other end is located within the wall 21 of a room 22, such as a kitchen, and is controlled by a damper or valve 23 mounted on said wall. The admission of air to, and consequent passage of air through, the pipe 20 is controlled entirely by manual adjustment of the damper or valve 23. A nozzle 70 device is mounted on the inner end of the pipe 17, within the furnace and adjacent to the dome 16, and said nozzle device preferably is made of metal by molding and is in one piece and imperforate except as hereinafter provided. The nozzle device is constructed with a collar member 24 adapted to be screwed on the pipe 17 and a discharge collar member 25 opposite thereto, said members being joined by tubular arched 75 members 26, in this instance eight in number, spaced circumferentially thereof and joining and communicating at their ends with said collar members. There is no communication between the tubular arched members and the space between them, but said space or spaces accommodate and permit the passage of heated air and burning gases and 80 flames around and between said members to the end of heating the air within and while 85 passing through said collar and arched communicating members.

In practical use the coal or similar fuel is placed on a grate 27, kindling is laid on said coal and paper or shavings is laid on 90 said kindling; the damper 23 is opened; and the paper or shavings is ignited in any suitable manner. Then all the doors and other draft devices such as are commonly found in said doors are closed and air is 95 drawn through the pipes 20 and 17 and the nozzle device to supply oxygen for combustion within the chamber. As the combustion 100 proceeds the coal is ignited and releases volatile carbon, and at the same time heat envelops and raises the temperature of the nozzle device above 600° F. Thereafter the air entering the combustion chamber of the furnace, through the nozzle device, and said nozzle device supplies substantially all of 105 110

the air employed therein, is heated to a temperature above 600° F. to the end of commingling said air with the volatile carbon released from the coal and creating a gas that will be consumed in the chamber and conserve the carbon, which otherwise might pass off, unburned, through the smoke flues.

The fuel supply may be replenished in any desired manner, such as by the introduction of coal through the open fuel door, and ashes may be shaken through the grate and removed through the open ash door; the opening of either the fuel or ash door temporarily modifying the operation of the furnace.

15 The air for combustion purposes may be drawn from any desired location, and such operation may be utilized to remove foul and noxious odors from any place, such as 20 a kitchen 22.

Any desired modification of the arrangement and location of parts may be made and I do not desire to be understood as limiting myself in such particular.

25 I claim as my invention—

1. A pipe adapted to be suspended within a furnace and a nozzle device suspended on

said pipe, said nozzle device having opposed spaced collars, one opening to said pipe and the other opening to said furnace, and intermediate, wholly outwardly arched communicating tubular members opening at their ends only to said collar members. 30

2. A pipe adapted to be suspended within a furnace, and a nozzle device suspended on 35 said pipe, said nozzle device having and including spaced annular collars, one opening to said pipe and the other opening only to said furnace, and intermediate, wholly outwardly arched, spaced, tubular members between and communicating at their ends only with said collar members. 40

3. A nozzle adapted for use in a hot-blast down-draft furnace, said nozzle comprising spaced annular collars having a common 45 axis, the spacing being on the line of said axis, and wholly outwardly-arched circumferentially-spaced tubular members between, connecting and communicating at their ends only with said collars. 50

Signed at Des Moines, in the county of Polk and State of Iowa, this 22d day of February, 1919.

JONATHAN J. SMITH.
